184,988

COMBINED STERN LIGHT AND SOCKET THEREFOR

Richard A. De Hart, Grand Rapids, Mich., assignor to
Attwood Brass Works, Inc., Grand Rapids, Mich., a
corporation of Michigan

Application January 14, 1957, Serial No. 44,485

Term of patent 14 years

(Cl. D48—20)

Fig. 1 is a side perspective view of a combined stern light and socket therefor showing my new design.

Fig. 2 is a side elevational view thereof.

Fig. 3 is a rear elevational view thereof.

Fig. 4 is a front elevational view thereof;

Fig. 5 is a top plan of the socket with the light post omitted for convenience of illustration only.

The posts are shown broken away in part in Figures 2, 3 and 4 for convenience of illustration only.

I claim:

The ornamental design for a combined stern light and socket therefor, as shown and described.
